Patented Nov. 26, 1918.

UNITED STATES PATENT OFFICE.

JOSEPH WARREN BECK, OF EL RITO, NEW MEXICO.

MUD-CHAIN HOOK.

1,285,597.

Specification of Letters Patent. Patented Nov. 26, 1918.

Application filed February 25, 1918. Serial No. 219,020.

To all whom it may concern:

Be it known that I, JOSEPH W. BECK, citizen of the United States, residing at El Rito, in the county of Rio Arriba and State of New Mexico, have invented certain new and useful Improvements in Mud-Chain Hooks; and I do declare the following to be a full, clear, and exact description of the invention, such as will enable others, skilled in the art to which it appertains to make and use the same.

This invention relates to fasteners, and it relates more particularly to an improved form of chain-end connectors.

One object of this invention is to provide a latch that automatically closes the hook-opening upon engaging a link of the chain therewith.

Another object is to provide an improved means for automatically locking the latch in its operative position.

Another object is to provide a device of this character in which the latch automatically opens, upon movement of the engaged chain link, in the direction for disengaging the latter from the hook.

Another object is to provide a hook of this character with a yielding resistance for the latch and also with a positive locking means therefor.

Another object is to provide a device of this character that consists of few and simple parts, so that the cost of manufacture is reduced to the minimum.

Other objects and advantages will become apparent to persons who read the following details of description in connection with the accompanying drawings, in which:

Figure 1 is a side elevation illustrating the angular position of a special form of chain link with relation to my improved form of hook or chain-end connector.

Fig. 2 is a view similar to Fig. 1, except that the hook is shown in longitudinal section.

Fig. 3 is a side elevation in which the chain ends are connected to the hook and aligned therewith.

Fig. 4 is a view similar to Fig. 3, except that it is shown in longitudinal section.

Fig. 5 is a sectional view along the line 5—5 of Fig. 4.

Fig. 6 is a transverse sectional view along the line 6—6 of Fig. 4.

Fig. 7 is a detail illustrating a combined pivotal connector and locking member.

Referring to these drawings in detail, in which similar reference characters correspond with similar parts throughout the several views, the reference character A designates a chain end or link of ordinary construction, and the reference character B designates a chain end or link of special construction. The special feature of this link consists in the formation of a square or non-cylindrical aperture 10 through one of its ends, this link being substantially U-shaped, as illustrated in Fig. 5, and its other end being apertured at 11.

A specially formed bolt extends through the apertures 10 and 11 and is provided with any suitable securing means 13. This member 12 is shown separately in Fig. 7, and constitutes the combined pivot and lock device, which is hereinafter described in detail.

A relatively thin and long tubular member or casing 14 is formed with a hook element 15, said hook element being formed by the provision of a slot or notch 16, which extends diagonally through one of the longitudinal edges of member 14, and this member is also provided with a pivot bearing 17, which consists of two aligned apertures through opposite sides of member 14, as more clearly shown in Fig. 5. The member 12 extends through the pivot bearing 17, while the notch 16 receives the link A.

In order to secure the link A in the notch 16, and to allow the link to be released from said notch, I provide a member 18. This member is also relatively thin and long and extends through the tubular member 14 and is longitudinally movable in the latter and guided in its movement by means of the inner surface in said member 14. Member 18 is formed with a diagonal slot or notch 19, the surface at one edge of which constitutes a cam 20, while the other end of slot 19 extends substantially parallel with the cam surface 20 and constitutes a tongue 21. The tongue 21 and the cam surface 20 are adapted to alternately extend across the slot 16, as illustrated in Figs. 4 and 2 respectively. The member 18 is provided with a longitudinally extending slot 22 (see Figs. 4 and 5), and this slot 22 is preferably circular and relatively wide at its ends and being relatively narrow at its intermediate portion, thereby providing shoulders 23 (see Figs. 2 and 4). These shoulders coöperate with an element 24 of the bolt 12 for lock-

ing the members 14 and 18 against movement relative to one another, as will be explained more fully hereinafter. The bolt or member 12 is flattened or slabbed at 25, 5 so as to be relatively thin and wide at this portion, and when the bolt is turned in the position shown in Fig. 2, the flattened portion allows movement of member 18 longitudinally in member 14, the relatively narrow portion of slot 22 passing across the member 12, so that the latter has relative movement from one to the other of said circular ends of slot 22. However, when the member 12 is turned into the position shown 10 in Fig. 4, the element 24 engages one of the elements 23 and locks the members 14 and 18 against relative movement. The member 12 is preferably cylindrical at 26 and 27, so that these cylindrical elements 20 constitute journals which rotate easily in the apertures 17 and the member 14. The member 12 is also provided with a square or non-cylindrical element 28 which fits in the aperture 10, so that the link B constitutes means for turning the member 12 with 25 relation to the members 14 and 18.

When the link B is swung to a position at an angle to the two members 14 and 18, the element 25 is in the position for allowing relative movement of elements 14 and 18; and when the several members of the device are in the relative position shown in Fig. 2, the link A may be engaged with the slot 16 by pressing said link toward the inner end of the said slot. When thus engaging the link with hook 15, the link A cooperates with the cam 20 for moving the member 18 into the closed position shown in Fig. 4, and in this closed position the 30 tongue 21 closes the slot 16 or closes the hook. Now, by swinging the link B into the position shown in Fig. 4, one of the shoulders 23 is engaged by the lock element 24, thereby preventing movement of member 18 with relation to member 14, and the tongue 21 effectively prevents the link A from becoming disengaged from the hook 15. Although the locking of members 14 and 18 is effected by the elements 23 and 24 35 when the links A and B are alined with the elements 14 and 18, it is to be understood that in practice the links A and B are swung somewhat beyond the alined or rectilinear position, owing to the curvature of the chain 40 50 55 60 65 70 75 80 85 90 95 100 105 110 115 120 125 130 around the side of a tire to which this device may be applied. It will be seen that when the links A and B are thus moved beyond their alined position, a greater surface of element 24 becomes operative. When it is desired to release the link A from the notch 16, a screw driver or similar tool may be employed as a lever for engagement between the tire and link B for swinging the latter into the position shown in Figs. 1 and 2, and while in this position,

it is only necessary to press the link A toward the opening of the notch 16, and the inner surface of the tongue 21 constitutes a cam which cooperates with the link A for effecting movement of member 18 to a position in which the tongue 21 no longer closes the notch 16. 70

In order that the member 18 shall not move with respect to the member 14, except when such motion is desired, I provide 75 the member 18 with shoulders 29, and between these shoulders I place a bow-spring 30, the ends of the spring being engaged with the shoulders 29, while its intermediate portion bears against the inner surface of 80 member 14 and is slidable along said inner surface, so that the frictional contact of the spring against said inner surface yieldingly resists movement of member 18 through member 14. 85

From the foregoing, it may be seen that I have provided a chain-end connector which is thoroughly practical, strong, compact, durable, convenient, thoroughly efficient, and comparatively inexpensive; and, 90 therefore, it is believed that this improved connector should meet with great commercial success and with great favor among users of such devices.

Although I have described this embodiment of my invention very minutely, it is to be understood that my invention is not limited to these exact details of construction and arrangement of parts, but I am entitled to make such minor changes that do not constitute a departure from the inventive idea disclosed in the foregoing description and appended claims. 95

What I claim as my invention is:

1. A chain-end connector comprising a 105 relatively thin and long member, provided with a chain-receiving notch extending diagonally inward through one edge, said member being provided with a pivot-bearing therethrough; a second relatively thin and long member, said second member being provided with a tongue and with a longitudinally extending slot, and a securing member extending through a chain link and through said pivot-bearing and through said 110 slot, the second said member being longitudinally slid able along the first said member and across the third said member so as to bring said tongue across said diagonal chain-receiving notch for securing the chain 115 in said notch. 120

2. A chain-end connector comprising a relatively thin and long tubular member provided with a chain-receiving notch extending diagonally inward through one 125 edge, said member being provided with a pivot-bearing therethrough, a second relatively thin and long member within said tubular member, said second member being provided with a tongue and with a longi- 130

- tudinally extending slot, and a securing member extending through a chain link and through said pivot-bearing and through said slot, the second said member being longitudinally slideable along the first said member and across the third said member, so as to bring said tongue across said diagonal chain-receiving notch for securing the chain in said notch.
- 10 3. A chain-end connector comprising a relatively thin and long member provided with a chain-receiving notch extending diagonally inward through one edge, said member being provided with a pivot-bearing therethrough; a second relatively thin and long member, said second member being provided with a tongue and with a longitudinally extending slot; and a combined pivot and locking member extending through a chain end and through said pivot bearing and through said slot, said second member being slideable longitudinally in the first said member and adapted to bring its tongue across the said diagonal notch for securing the chain in said notch, said combined pivot and locking member being operable to engage with a side of said slot for locking the second said member in its chain-securing position.
- 20 4. A chain-end connector comprising a relatively thin and long member provided with a chain-receiving notch extending diagonally inward through one edge, said member being provided with a pivot-bearing therethrough; a second relatively thin and long member, said second member being provided with a tongue and with a longitudinally extending slot; and a combined pivot and locking member extending through a chain end and through said pivot bearing and through said slot, said second member being slideable longitudinally in the first said member and adapted to bring its tongue across the said diagonal notch for securing the chain in said notch, said combined pivot and locking member being operable by the manipulation of said chain end for effecting locking engagement of the last said member with the second said member.
- 30 5. A chain-end connector comprising a relatively thin and long member provided with a chain-receiving notch extending diagonally inward through one edge, said member being provided with a pivot-bearing therethrough; a second relatively thin and long member, said second member being provided with a tongue and with a longitudinally extending slot; and a combined pivot and locking member extending through a chain end and through said pivot bearing and through said slot, said second member being slideable longitudinally in the first said member and adapted to bring its tongue across the said diagonal notch for securing the chain in said notch, said combined pivot and locking member being operable to engage with a side of said slot for locking the second said member in its chain-securing position.
- 40 6. A chain connector comprising a hooked member provided with a pivot bearing; a second member, the latter formed with a shoulder and with a tongue and being mounted for movement to bring its tongue in position to close the hook of the first said member; and a combined pivot and locking element non-rotatably engaged with a chain and extending through said pivot bearing and engageable with said shoulder so as to lock the second said member against movement with relation to the first said member.
- 70 7. The combination of a relatively thin and long member formed with a pivot bearing and a hook and a guide, the latter extending longitudinally thereof; a second relatively thin and long member, said second member being formed with a tongue and being mounted for movement along said guide to bring said tongue into position for closing said hook, said second member being formed with a slot having relatively wide ends and a narrow intermediate portion; a combined pivot and locking member provided with a cylindrical portion and a slabbed portion, said cylindrical portion being rotatable in said pivot bearing, said slabbed portion being adapted to slide through or be locked by said narrow portion of the slot, according to the relative position of the second said member and the third said member; and means for rotating the third said member and thereby changing said relative positions.
- 80 8. The combination of a relatively thin and long member formed with a pivot bearing and a hook and a guide, the latter extending longitudinally thereof; a second relatively thin and long member, said second member being formed with a tongue and being mounted for movement along said guide to bring said tongue into position for closing said hook, said second member being formed with a slot having relatively wide ends and a narrow intermediate portion; a combined pivot and locking member provided with a cylindrical portion and a slabbed portion, said cylindrical portion being rotatable in said pivot bearing, said slabbed portion being adapted to slide through or be locked by said narrow portion of the slot, according to the relative position of the second said member and the third said member; and means for rotating the third said member and thereby changing said relative positions.
- 90 9. The combination of a relatively thin and long member formed with a pivot bearing and a hook and a guide, the latter extending longitudinally thereof; a second relatively thin and long member, said second member being formed with a tongue and being mounted for movement along said guide to bring said tongue into position for closing said hook, said second member being formed with a slot having relatively wide ends and a narrow intermediate portion; a combined pivot and locking member provided with a cylindrical portion and a slabbed portion, said cylindrical portion being rotatable in said pivot bearing, said slabbed portion being adapted to slide through or be locked by said narrow portion of the slot, according to the relative position of the second said member and the third said member; and means for rotating the third said member and thereby changing said relative positions.
- 100 10. The combination of a relatively thin and long member formed with a pivot bearing and a hook and a guide, the latter extending longitudinally thereof; a second relatively thin and long member, said second member being formed with a tongue and being mounted for movement along said guide to bring said tongue into position for closing said hook, said second member being formed with a slot having relatively wide ends and a narrow intermediate portion; a combined pivot and locking member provided with a cylindrical portion and a slabbed portion, said cylindrical portion being rotatable in said pivot bearing, said slabbed portion being adapted to slide through or be locked by said narrow portion of the slot, according to the relative position of the second said member and the third said member; and means for rotating the third said member and thereby changing said relative positions.
- In testimony whereof I have hereunto set my hand in the presence of two subscribing witnesses.
